US00D755846S

(12) United States Design Patent (10) Patent No.: US D755,846 S
Lee (45) Date of Patent: * May 10, 2016

(54) DISPLAY SCREEN OR PORTION THEREOF
WITH ICON

(71) Applicant: Samsung Electronics Co., Ltd.,
Suwon-si (KR)

(72) Inventor: Seung-Myung Lee, Seoul (KR)

(73) Assignee: Samsung Electronics Co., Ltd.,
Suwon-si (JP)

() Term: 14 Years

(21) Appl. No.: 29/491,273

(22) Filed: May 20, 2014

(30) Foreign Application Priority Data

Feb. 21, 2014 (KR) 30-2014-0008993

(51) LOC (10) Cl. 14-04

(52) U.S. Cl.

USPC D14/492

(58) Field of Classification Search

USPC D14/485-495

CPC ... G06F 3/048; G06F 3/0481; G06F 3/04817;
G06F 3/0482

(57) CLAIM

I claim the ornamental design for a display screen or portion thereof with icon, as shown and described.

DESCRIPTION

The sole FIGURE is a front view of a display screen or portion thereof with icon showing my new design.

The dot dash line in the FIGURE represents an unclaimed boundary line and forms no part of the claimed design.

1 Claim, 1 Drawing Sheet

U.S. Patent
